ATTORNEY

UNITED STATES PATENT OFFICE.

WILLIAM LANE GILLETTE, OF FLAGTOWN, NEW JERSEY.

FUNNEL.

1,290,968.

Specification of Letters Patent.

Patented Jan. 14, 1919.

Application filed January 7, 1918. Serial No. 210,681.

To all whom it may concern:

Be it known that I, WILLIAM LANE GILLETTE, a citizen of the United States, residing at Flagtown, in the county of Somerset and State of New Jersey, have invented certain new and useful Improvements in Funnels, of which the following is a specification.

This invention relates to a funnel and has for its object the production of a simple and efficient funnel which will automatically close as soon as a receptacle which is being filled therefrom receives the desired amount of liquid.

15 Another object of this invention is the production of a simple and efficient means for indicating to the operator that a receptacle which is being filled through the funnel, has received a sufficient quantity of liquid.

20 With these and objects in view this invention consists of certain novel constructions, combinations and arrangements of parts as will be hereinafter fully described and claimed.

25 In the drawings:

Figure 1 is a vertical section through the funnel.

Fig. 2 is a top plan view of the indicator carried by the funnel.

30 Fig. 3 is a section taken on line 3-3 of Fig. 1.

By referring to the drawing, it will be seen that 1 designates the body of the funnel which is provided with a reduced neck 2 upon the lower end of which is mounted a resilient washer or ceiling ring 3.

A bracket 4, which is adapted to support an indicator cap, is carried by the funnel 1 and is provided with a substantially circular disk 5 arranged intermediate the ends thereof. A casing 6 is carried by the disk 5 and is substantially tubular in structure.

A transparent cover 7 is carried by the casing 6, upon the upper end thereof, and an indicator cap 8 is mounted within the casing 6 and is carried by the plunger rod 9. This plunger rod 9 is provided with a conical neck 10 near the upper end thereof placed below the cap 8. The lower edge of the conical neck 10 projects beyond the plunger rod 9 for producing a shoulder 11, which shoulder is adapted to be engaged by means of the fork-shaped end 12 of the latching bar 13.

55 A valve 14 is carried by the lower end of the plunger rod 9 and this valve 14 carries

a conical shaped shedding device 15 upon the top thereof which is adapted to prevent the liquid from splashing upon the top of the valve 14 and is also adapted to cause the liquid to be shed over the sides of the valve 14. The side edges 16 of the valve 14 are substantially concave for the purpose of permitting the valve 14 to tightly wedge itself upon the washer 3, which washer 3 constitutes a valve seat.

A substantially dome-like plate 17 is carried within the reduced neck 2 and constitutes a means for preventing the liquid from splashing through the neck 2 and this dome-like plate 17 is provided with suitable apertures 18 formed therein for the purpose of permitting liquid to readily pass through the plate 17.

A handle 19 is secured to the funnel 1 and is provided with a projecting shank 20 within which shank 20 is mounted a coil spring 21. The latching bar or plate 13 is provided with an enlarged head 22 which works within a socket 23 formed in the handle 19 and this head 22 is engaged by the spring 21 for the purpose of forcing the latching bar 13 at all times against the plunger rod 9. A thumb push button 24 is carried by the latching bar 13 and this push button 24 works within a slot 25 formed in the shank 20.

The cap plate 8 is provided with the legend "Full", and as soon as the valve or float 14 is forced upon the washer of valve seat 3, the cap plate 8 will be forced upwardly within the casing 6 thereby causing the conical neck 10 to ride over the inner end of the latching bar 13, the latching bar 13 catching under the shoulder 11 and holding the rod 9 in a set position, in this way supporting the cap plate 8 in the top end of the casing 6 and holding the float valve 14 in a closed position. In this way the operator may see by observing the indicator that a desired amount of liquid has been placed within a receptacle which is being filled through the funnel and at the same time the lower end of the funnel will be closed thereby preventing a receptacle which is being filled by the funnel, from overflowing.

What is claimed is:

1. A funnel comprising a body provided with a reduced neck, a bracket adapted to support an indicator cap carried by said body, a plunger rod extending through said bracket, a valve carried by the lower end of

said plunger rod, a sealing ring carried by the lower edge of said reduced neck, said valve adapted to be seated upon said sealing ring for constituting a closure for the lower end of said body, a liquid diffusing means carried within said neck, and a spring pressed latching means slidably mounted upon said bracket and engaging said plunger rod for locking said plunger rod in a closed position.

2. A funnel of the class described comprising a body, a reduced neck carried by said body, a dome-shaped diffusing plate carried within said reduced neck and provided with radiating apertures widened toward their outer ends, a plunger rod extending through said plate, a valve carried by the lower end of said plunger rod, a sealing ring carried by the lower edge of said reduced neck and constituting a valve seat for said valve, a supporting bracket carried by the upper end of said body and constituting a guide for the upper end of said plunger rod, a flat latching bar slidably mounted upon said bracket and adapted to automatically engage said plunger rod for locking said plunger rod in a raised position.

3. A funnel of the class described comprising a body provided with a discharge opening, a bracket adapted to support an

indicator cap carried by said body, a plunger rod extending through said bracket, a valve carried by said plunger rod for closing the discharge opening at selected intervals, a conical neck carried near the upper end of said plunger rod, and indicators carried by the upper end of said plunger rod, said conical neck provided with an abrupt lower end, a flat sliding latching bar slidably mounted upon said bracket and provided with a notched inner end adapted to fit under said abrupt shoulder of said plunger rod thereby constituting a positive locking means for holding said plunger rod in a raised position, a handle secured to said body, said handle provided with a longitudinally extending bore formed therein, said latching bar extending through said bore, a knob carried by said latching bar and extending through said handle for facilitating the manual operation of said latching bar, and means for yieldably forcing said latching bar in engagement with said plunger rod.

In testimony whereof I affix my signature in presence of two witnesses.

WILLIAM LANE GILLETTE.
